UNITED STATES PATENT OFFICE

SABIN KAROL SALCMAN, OF KORYCIN, BIALYSTOK, POLAND

ADJUSTABLE OAR FOR ROWBOATS

Application filed May 31, 1930. Serial No. 457,849.

This invention relates to a new and useful device in the nature of oars, particularly adapted for use in connection with row boats and the like, as a means of propelling or rowing a row boat.

The object of the invention is to provide a pair of oars of novel construction and arrangement of parts, hereinafter more fully described, claimed, and illustrated in the accompanying drawings, in which:

Fig. 1 shows a fragmentary top plan view of a row boat equipped with a pair of my improved oars.

Fig. 2 shows a transverse sectional view thereof.

Fig. 3 shows a top plan detail view of the supporting member, as employed as a means of attaching my improved oars to a row boat.

Fig. 4 shows a side elevational fragmentary detail view of my improved oars, and the supporting members employed as a means of attaching same to a row boat.

Fig. 5 shows a fragmentary sectional view taken on the line 5—5 of Fig. 4.

Fig. 6 shows a modification of my improved blade member as embodied in my improved device.

As here embodied my improved device comprises a supporting member consisting of a pair of base members 10, attached to the sides 11, by the brackets 13, extended therefrom, as clearly shown in Figs. 1 and 2, of the accompanying drawings. The brackets 14 and 15, are pivotally attached as at 16, 17, and 18 and 19, respectively, by threaded members, set screws or the like, carried in the lug elements 20 of the base members 10. The extremities of the threaded members 16, 17, 18, and 19, engage in apertures formed in the extremities of the brackets 14 and 15, and are secured therein, as may be desired by the nuts 21, threadedly attached to the threaded members 16, 17, 18, and 19. The above described construction being such as will permit the said brackets 14 and 15 to be pivoted, as may be desired for the purpose as hereinafter set forth.

The handle member 22, is provided with a free extremity 23, formed or shaped so as to provide a grip, such as usually used for

the purpose of gripping or holding an oar as a means of rowing a boat with the said oar. The plate member 24, is adjustably attached to the handle member 22, by the bolts 25, adapted to engage in any of the desired apertures 26, formed in the handle member 22, and in the plate member 24, as a means of adjustably attaching the plate member 24 to the handle member 22. The plate member 24 is provided with notches 27, adapted to engage in similar shaped protruding elements of the handle member 22, as a means of securing the said engagement of the plate member 24 with the handle member 22.

The plate member 24 is provided with a lug element 28, having an aperture adapted to receive the pin 29, pivotally attached, as at 30, to the extended portion of the above mentioned bracket 15. The pin 29, has pivotally attached at its free extremity, a locking member 31, as a means of pivotally securing the handle member 22 to the bracket 15.

The blade member 32, is provided with a free extremity 33, formed or shaped, so as to provide a blade, such as usually used for the purpose of propelling or rowing a boat, when the said blade is pulled through the water. The blade member 32, is similarly pivotally attached, as is the handle member 22, to the free extremity of the above mentioned bracket 14, as hereinbefore described and set forth, similar elements having the same reference numerals in the accompanying drawings.

The handle member 22 is pivotally attached to the blade member 32, intermediate the brackets 14 and 15, by a threaded member 34 carried in the brackets 35 and 36, attached to the blade member 32 and handle member 22, respectively.

The above described construction being such as will permit the row boat 12 to be rowed. It being understood that the handle member 22, and the blade member 32, may be adjustably attached to the brackets 15 and 14, respectively, as a means of increasing the movement of the blade member 32 relative to the handle member 22. It being obvious that the above described construction is such as will permit the handle member 22 to be

positioned in an upward or downward position, as may be desired, to accommodate the person rowing the said boat.

In Fig. 6 of the accompanying drawings, 5 the supplementary blade section 37, is hinged as at 38, to the blade member 32'. The rod 38', is pivotally attached, as at 39, to the bracket 40, attached to the supplementary blade section 37. The extended extremity of 10 the rod 38', is adapted to slidably engage in an aperture formed in the block section 41, pivotally attached, as at 42, to the bracket 43, attached to the blade section 32'. The threaded members 44 are adjustably attached 15 to the extended extremity of the rod 38'. The above described construction being such as will securely hold the supplementary blade section 37 in any desired relative position to the blade section 32'. The supplementary 20 member section 37 may be pivotally mounted on the brackets 14 and 15, and the both blade sections 37 and 32' may be used as the blade member 32.

It will be understood that one or more 25 pairs of my improved oars are used, as is customary practice in devices of this particular nature.

Having thus described my invention, what 30 I claim as new and desire to protect by Letters Patent of the United States is as follows:

- 35 1. In a device of the class described, a blade member comprising a supplementary blade section, a blade section pivotally connected to the supplementary section and means for holding the said sections in fixed adjusted positions, comprising a rod pivotally attached to the supplementary blade section, and means for pivotally and adjustably holding said rod to the blade section.
- 40 2. In a device of the class described, a blade member comprising a supplementary blade section, a blade section pivotally connected to the supplementary section and means for holding the said sections in fixed adjusted positions, comprising a rod pivotally attached to the supplementary blade section, and means for pivotally and adjustably holding said rod to the blade section, comprising a bracket fixed to said blade section, a block member pivotally mounted on said bracket and formed with an aperture through which said rod slidably engages, and means for adjustably holding said rod in fixed positions in said aperture.
- 45 3. In a device of the class described, a blade member comprising a supplementary blade section, a blade section pivotally connected to the supplementary section and means for holding the said sections in fixed adjusted positions, comprising a rod pivotally attached to the supplementary blade section, and means for pivotally and adjustably holding said rod to the blade section, comprising a bracket fixed to said blade section, a block member pivotally mounted on said bracket and formed

with an aperture through which said rod slidably engages, and means for adjustably holding said rod in fixed positions in said aperture, comprising a nut threadedly engaged on the rod on one side of said block member, and a second nut threadedly engaged in the rod on the other side of said block member.

In testimony whereof I have affixed my signature.

SABIN KAROL SALCMAN.
